UNITED STATES PATENT OFFICE.

GUY C. HEILMAN, OF PHILADELPHIA, PENNSYLVANIA.

MELTING TANK.

1,422,858.

Specification of Letters Patent. Patented July 18, 1922.

Application filed October 20, 1919. Serial No. 331,804.

To all whom it may concern:

Be it known that I, GUY C. HEILMAN, a citizen of the United States, and resident of the city of Philadelphia, in the county 5 of Philadelphia and State of Pennsylvania, have invented certain new and useful Improvements in Melting Tanks, of which the following is a specification.

My invention relates to melting tanks, and 10 more particularly to tanks in which glass is melted for the manufacture of bottles or other articles. The object of my present invention is to obtain a uniform heating action within the melting tank, and to utilize 15 fully the caloric value of the fuel employed. Other features and advantages of this invention will appear from the description following hereinafter.

In the accompanying drawings I have 20 illustrated a typical example of a glass-melting tank constructed and heated in accordance with my present invention. Fig. 1 is partly a top view of such tank, and partly a horizontal section thereof on line 1—1 of 25 Fig. 2; Fig. 2 is a side elevation of the tank; Fig. 3 is a longitudinal vertical section on line 3—3 of Fig. 1; and Fig. 4 is a transverse vertical section on line 4—4 of Fig. 3.

Fuel, say, producer gas, is supplied 30 through flues or mains 10 extending horizontally at each side of the tank 11, generally below the floor line. From these mains, which may serve a plurality of melting tanks, upright pipes 12 lead to horizontal 35 pipes 13, the connection of each pipe 12 with the corresponding pipe 13 being suitably controlled, as by a damper 14. The discharge end of each pipe 13 communicates 40 with a mixing and combustion chamber 15, discharging into the main chamber or melting chamber 16 of the tank 11, at a point slightly below the roof 17 of said chamber. Each of the mixing and combustion chambers 15 is contracted toward its outlet, both 45 in height, as shown in Fig. 4, and in width, see Fig. 1. The bottom of the mixing chamber 15 may also be inclined downwardly toward the outlet, as indicated in Fig. 4, but this is not essential. Into the tapering portion 50 of each mixing chamber 15 projects the outlet end of an air-nozzle 18, located at the upper portion of said chamber, and inclined downwardly toward the outlet of the mixing and combustion chamber. This air-nozzle has a lateral connection with an air-supply pipe 19, receiving heated air as set

forth below. The tube forming the air-nozzle 18 is continued upwardly beyond the junction of said tube with the pipe 19, and at the upper end of this tube is located a 60 peep-hole 18' closed by mica or other transparent material, so as to afford the possibility of watching the progress of combustion in the chamber 15, without however admitting air through the tube end containing 65 the peep-hole 18'. The chambers 15 are spaced evenly on each side of the melting chamber 16, but preferably the combustion chambers 15 at one side are out of transverse alignment with those on the other side 70 of the melting chamber, this staggered arrangement being indicated clearly in Fig. 1. Between each two combustion chambers 15 on the same side of the tank, and in transverse alignment with one of the combustion 75 chambers 15 on the other side of the tank 11. I locate an additional peep-hole 20, preferably made with a cover of mica or other transparent material. Through these peep-holes 20, which preferably flare inwardly, 80 I am enabled to watch from each side wall of the tank, the combustion in the chambers 15 at the opposite side of the tank, and also the condition of the molten glass in the chamber 16, the level of the glass being indicated at A. A bridge wall 21 of usual or approved construction separates the melting chamber 16 from the end chamber, or clearing and working chamber 22 of the tank, the clear molten glass passing into 90 the chamber 22 through an opening 21' located in the bridge wall 21 below the glass level A.

The upper ends of the air-supply pipes 19 are connected with the intermediate 95 chambers 23 of air-heaters 24 located at each side of the tank 11, above the roof 17 thereof. Each of the chambers 23 receives air at one end through a pipe 25, the air being generally forced through by means of a 100 blower or the like (not shown). Each of the heaters 24 also has an upper chamber 26 and a lower chamber 27 connected at one end by an upright channel 28, while at the other end the chamber 26 (above the chamber 23) has an outlet or stack connection 29, and the lower chamber 27 has an intake connection 30 communicating with the melting chamber 16. It will be understood that the connections 29, 30 of the same heater 24 are 105 superposed, or at least at the same end of the heater; but preferably the connections 110

- 29, 30 of one heater 24 are at the forward portion of the melting chamber, and the connections of the other heater at the rear end of said chamber, as will be obvious from 5 Fig. 1 in connection with the other views. By this diagonal arrangement I secure certain important advantages as regards the passage of the hot gases from the melting chamber 16 to the stack connections 29. 10 Dampers 31, 32 are shown to control respectively the stack connections 29 and the connections between the chambers 23 and the several nozzles 18. Baffles 33 are shown in the lower portions 15 of the pipes 13 between the pipes 12 and the outlets of the nozzles 18. In operation, fuel will pass from the mains 10 to the pipes 12 and 13, thus reaching the mixing and combustion chambers 15, 20 and becoming mixed therein with the air supplied through the pipes 19, forms a whirling ball of fire in each of said chambers, which ball of fire may be watched through the corresponding peep-hole 18'. 25 Any foreign matter contained in the fuel current is thrown down in front of the baffle 33, which also deflects said current upwardly toward the outlet of the air-nozzle 18, so as to insure a more thorough mixture of fuel (generally producer gas) and air. The hot gases from the chambers 15 pass into the melting chamber 16 and keep the glass therein in a molten condition. It will be observed that the hot gases are thoroughly distributed within said chamber, owing to the fact that the combustion chambers at one side of the tank are out of line with those on the opposite side. The peep-holes 20 afford an opportunity to watch the 30 molten glass and the combustion chambers arranged in transverse alignment with the respective peep-holes on the opposite side of the melting chamber 16. The glass passes through the skipper-hole 21' of the bridge-wall 21, from the melting chamber 16 to the clearing and working chamber 22, from which it is delivered to molds or other apparatus in any well-known or approved manner (not shown). The hot gases pass 35 out from the chamber 16 through the connections 30, of which there are two, located at diagonally-opposite corners of the melting chamber 16, that is to say, one at the forward corner on one side (say, the right, 40 Fig. 1), and the other at the rear corner on the opposite (left hand) side. With this special arrangement, the maximum distance from a point of the melting chamber to one of the outlet connections is much smaller 45 than if both connections were at the same end of the melting chamber, since in that case the hot gases from points at the other end of the melting chamber would have to travel the full length of said chamber in 50 order to reach one of the outlet connections.

The particular arrangement of inlets and outlets devised by me also insures a thorough distribution of the heating gases within the melting chamber. The gases rise through the outlet connections 30 into the horizontal 70 chambers 27, travel in said chambers lengthwise of the melting chamber (forward in one of the heaters 24 and rearward in the other), and at the opposite end of the said lower chamber 27 the gases pass upward 75 through the channel 28 into the upper horizontal chamber 26. They then travel lengthwise in said upper chamber, in the direction opposite to their travel through the corresponding lower chamber 27, and, at the 80 end adjacent to the connection 30, the hot gases pass to the stack through the connections 29. It will be observed that the hot gases are thus led along the air-chamber 23, both above and below the same, and around 85 one end thereof, so that the air supplied to said chamber through the pipe 25 is thoroughly heated in said chamber 23, while passing therethrough on its way to the connections or pipes 19 leading to the air-nozzles 18. The heating action in the chambers 23 may be regulated by adjusting the valves or dampers 31 and 32, or either of them, while the combustion in chamber 15 can be regulated by adjusting the fuel-valves 14 or 90 the air-valves 32, or both.

Various modifications may be made without departing from the nature of my invention as set forth in the appended claims.

I claim as my invention:

100

1. A device of the class described, provided with a main chamber, combustion chambers discharging into said main chamber at one side, and peep-holes located in the opposite wall of the main chamber, in 105 line with the said combustion chambers.

2. A device of the class described, provided with a main chamber and combustion chambers discharging into it at opposite sides, the combustion chambers on one side 110 being out of line with those on the other side, and peep-holes located at each side, between the combustion chambers of the same side, and in line with the combustion chambers of the other side.

115

3. A device of the class described, provided with a main chamber of substantially rectangular shape having outlets at diagonally-opposite corners, combustion chambers discharging into said main chamber at 120 opposite sides thereof, and air-heaters having air-paths delivering air to said combustion chambers, and hot-gas paths receiving gases from said outlets.

4. A device of the class described, provided with a main chamber of substantially rectangular shape having outlets at diagonally-opposite corners, combustion chambers discharging into said main chamber, and air-heaters each provided with an ap- 125 130

- proximately horizontal air-chamber delivering air to one of said combustion chambers, and hot-gas chambers located above and below said air-chamber and connected with hot-gas paths located above and below said air-path and connected with said gas-outlet.
- 5 7. A device of the class described, provided with a main chamber having a gas outlet, a combustion chamber discharging into said main chamber, and an air-heater extending longitudinally above said main chamber and provided with a longitudinal 25 air-chamber delivering air to said combustion chamber, and hot-gas chambers located longitudinally above and below said air-chamber respectively, and connected with each other at one end, the other end of the 30 lower chamber being connected with the outlet of the main chamber, while the other end of the upper chamber has an outlet connection.
- 10 5. A device of the class described, provided with a main chamber of substantially rectangular shape having outlets at diagonally-opposite corners, and inlets for a heating medium along two opposite walls.
- 15 6. A device of the class described, provided with a main chamber having a gas outlet, means for discharging a heating medium into said chamber, and an air-heater extending longitudinally above said main 35 chamber and provided with an air-path delivering air to said heating medium, and
- 20

7. A device of the class described, provided with a main chamber having a gas outlet, a combustion chamber discharging into said main chamber, and an air-heater extending longitudinally above said main chamber and provided with a longitudinal 25 air-chamber delivering air to said combustion chamber, and hot-gas chambers located longitudinally above and below said air-chamber respectively, and connected with each other at one end, the other end of the 30 lower chamber being connected with the outlet of the main chamber, while the other end of the upper chamber has an outlet connection.

In testimony whereof I have signed this 40 specification.

GUY C. HEILMAN.
